UNITED STATES PATENT OFFICE.

GUSTAV DE GRAHL, OF BERLIN-ZEHLENDORF-WEST, GERMANY.

FEED VALVE FOR LOCOMOTIVES.

Application filed March 11, 1925, Serial No. 14,818, and in Germany November 14, 1924.

For locomotives a device has already been suggested by means of which, when the regulating valve is closed, individual groups of accessories of the locomotive, such as air pumps and feed pumps, and also the heating apparatus, are supplied with wet steam, while when the regulating valve is opened, superheated steam instead of wet steam is supplied to these groups through a differential control piston. It has now been found that certain of the accessory groups, such as the injectors and the auxiliary blower, are preferably worked only with wet steam, and in the case of the known apparatus another special steam connection is therefore necessary, which holds wet steam alone in storage and enables it to be supplied to the last-mentioned auxiliary groups. In the case of the known arrangement moreover there is the great danger that by the use of a superheated steam the heating hose pipes, which establish the connection between the individual carriages, are severely attacked and after a short time are destroyed. These disadvantages are removed by the present invention, a feed valve for locomotives being provided which by its special construction renders the steam connection for obtaining wet steam superfluous and on the other hand gives the possibility of adding a predetermined quantity of superheated steam to the wet steam employed for heating, that is to say, only just so much as is requisite in order to prevent condensation in the heating pipe, without the heating hose pipes thereby being particularly attacked. The invention is illustrated by way of example in the accompanying drawing, wherein Figure 1 is a longitudinal section through the feed valve, and Figure 2 an elevation thereof on a reduced scale. According to the invention, spaces 2 and 3, separated from one another, are provided in the casing 1 of the feed valve. The feed valve is arranged in any desired position, at the steam dome or preferably on the boiler barrel, as shown in Figure 1, where 4 indicates the wall of the boiler. On the side facing the steam space 5 the feed valve is entirely open or preferably is provided with separate passages 6', shown in dotted lines in Figure 1, so that wet steam can flow through the feed valve in the direction of the arrow 6, the steam passing through a space 7 into the space 2 and from here steam can be taken off through pipe unions 8. In the interior of the feed valve are provided two concentric bores 9 and 10 for the reception of a differential control piston 11. The movement of this control piston can be prevented or limited should occasion require by a screw spindle 12. The bore 10 communicates through a pipe 13 with the superheater chamber, and passages 14 are provided through which in one position of the differential control piston, the superheated steam from the superheater chamber can enter the space 3. Further passages 15 are arranged, which in the other position of the differential control piston allow wet steam to pass out of the chamber 2 into the space 3. Pipe unions 16 enable superheated steam to be taken out of the space 3, and in the case of a special constructional form, a pipe is branched off from such a union 16 to an injector 17, which is connected to a union 8 for wet steam as shown in Figure 2. The method of working of the apparatus is as follows: If the regulating valve is opened, the superheated steam acts on the part of the differential control piston having the larger diameter so that the said piston is pushed towards one of its limiting positions and allows superheated steam to enter the space 3 through the passages 14. Consequently through the unions 16 superheated steam is made available for the feed and air pumps. Independently of this the space 2 is in constant communication with the wet steam from the boiler, which enters this space in the direction of the arrows 6, and this wet steam can be supplied through the pipe unions 8 to the other auxiliary groups, the injectors, the auxiliary blower, the steam heating apparatus and the like. Through the injector 17 some superheated steam can be drawn by suction out of the space 3 by the wet steam and fed to the wet steam, according to the adjustment of this injector 17. In this manner the danger of damaging the heating hose pipes by raising the temperature of the wet steam is obviated and at the same time condensation in the wet steam pipes is prevented. If the regulating valve not shown in the drawing is closed the pressure in the pipe 13 and the space of the bore 10 ceases, and

the pressure of the wet steam on the other side of the differential control piston displaces the latter into its other limiting position. By this means the passages 15 are 5 opened, so that wet steam from the space 2 can now enter the space 3 in the direction of the arrow 18 and is supplied to the groups that are fed with superheated steam when the regulating valve is opened. The 10 passages 14 are at the same time closed, so that the wet steam cannot escape here from the space 3.

What I claim is:—

1. A feed valve of the type for controlling 15 the passage of superheated and wet steam respectively from a superheater and boiler to an injector comprising a casing having superposed chambers therein, the lower of which is provided with inlets for superheated 20 and wet steam, each of said chambers being also provided with outlets, a differential cylinder in said casing arranged concentrically of both of said chambers, and a differential piston in said cylinder for controlling the passage of wet and superheated steam through said chambers and casing.

2. A feed valve of the character described, comprising a casing, a chamber arranged within the casing, a cylinder body in the 25 casing having two coaxial bores of different widths, a differential piston mounted in the bores for controlling the passage of superheated steam from a heater to an injector, passages extending through the cylinder 30 body communicating with the chamber, an outlet leading from the chamber, a second chamber in the casing, passages connecting the second chamber with the cylinder at points near the respective ends of the 35 piston, an inlet for superheated steam for the second chamber and controlled by the lower part of the piston.

3. A feed valve for the type for controlling 40 the passage of superheated and wet steam respectively from a superheater and boiler to an injector, comprising a casing

provided with superposed chambers, the lower of which is provided with inlets for superheated and wet steam, both of said chambers being also provided with outlets, 50 a differential cylinder body in said casing and arranged concentrically of both of said chambers, a differential piston in said cylinder for controlling the passage of wet and superheated steam through said chambers 55 and casing, passages provided in the casing and cylinder body for conducting wet steam to the upper of said chambers, other passages provided in the casing adjacent the upper and lower ends of the lower chamber 60 and both parts of said differential cylinder body and respectively controlled by the upper and lower parts of the piston.

4. A feed valve of the type set forth in 65 claim 3, wherein a manually operable hand wheel is mounted in the casing for controlling the position of the piston.

5. A feed valve of the type for controlling 70 the passage of superheated steam from a superheater to an injector, comprising a casing, a cylinder body within said casing provided with two coaxial bores of different width, a differential piston mounted in said bores, superposed chambers arranged in the casing about and above the cylinder body, 75 the lower piston controlling the flow of superheated steam into said lower chamber, the upper chamber being in constant communication with the upper of said pistons, passages within the cylinder body for conducting wet steam to the upper chamber, an outlet leading from the lower chamber and adapted to be connected to the injector, and a second outlet in the upper chamber controlled by said upper piston for permitting 80 wet steam to pass through the outlet to the injector, substantially as and for the purposes set forth.

In testimony whereof I have signed my name to this specification.

GUSTAV DE GRAHL.
